TUBULAR LANTERN.

1,202,750.

Specification of Letters Patent. Patented Oct. 24, 1916.

Application filed September 2, 1915. Serial No. 48,701.

To all whom it may concern:

Be it known that we, EDWARD J. McDADE and THEODORE A. GLENDE, citizens of the United States, and residents of Rochester, 5 in the county of Monroe and State of New York, have invented certain new and useful Improvements in Tubular Lanterns, of which the following is a specification.

The object of this invention is to provide 10 a tubular lantern with improved means for securing the air-tubes and other parts to the oil-font, so as not only to provide strong and durable connections between these parts, but also, in the preferred embodiment of the 15 invention, to dispense with the use of solder for this purpose.

The foregoing object is attained by the use of connecting means comprising, particularly, a plate or sheet-metal member 20 which lies on top of the oil-font and is connected with the oil-font, on the one hand, and on the other hand with the air-tubes or other parts which are to be attached to the oil-font. In order that a secure connection 25 may be formed, without the necessity for using solder, the plate just referred to is preferably attached to the oil-font by means of a mechanical lock or joint, while it is preferably attached to the air-tubes and 30 other parts by connecting-members which pass over these parts, and of which the ends pass through openings in the plate and are seated between this plate and the top of the oil-font.

Other features of the invention will be set forth in connection with the following description of the preferred embodiment of the invention.

In the accompanying drawings:—Figure 1 40 is a front-elevation of a tubular lantern embodying the present invention; Fig. 2 is a vertical section, on the line 2—2 in Fig. 1, of the lower part of the lantern, on a larger scale than Fig. 1; Fig. 3 is a section on the 45 line 3—3 in Fig. 1, looking from right to left in the latter figure; and Fig. 4 is a front-elevation of a portion of the lantern, showing, in detail, the connection between one of the air-tubes and the oil-font.

The invention is illustrated as embodied 50 in a tubular lantern of which the general form and construction are well known. The oil-font 10, as shown particularly in Fig. 2, is of the usual form, except for the fact that 55 it is provided, near the top, with an annular

recess or groove 11, which is preferably formed by rolling the sheet-metal after it has been drawn to form the body of the oil-font. An important feature of the present invention resides in a disk or plate 12 60 of sheet-metal, which lies on top of the oil-font. This plate has a depending peripheral flange 13, of which the lower edge is swaged or bent into the recess 11, so that the plate is securely fixed, at its margin, to the oil- 65 font by an interlocking joint, and without the necessity of solder. The plate 12 is perforated to receive the usual burner-cup 14, and this burner-cup thus serves as further means of attachment between the plate 12 70 and the oil-font, in addition to performing the usual function of securing together the oil-font and the air-chamber 15.

The air-tubes 16 of the lantern are of the usual form except for their lower end- 75 portions. These end-portions are formed as shown in Fig. 3, with flat lower surfaces which rest upon the upper surface of the plate 12. The air-tubes are secured to the plate by means of fastening-members 17 in 80 the form of strips of sheet-metal, these members being bent to conform them to the tubes, and having end-portions 18 and 19 which extend downwardly through slots in the plate 12, and are then bent outwardly 85 so as to lie between the plate and the top of the oil-font. The sharp bends in these end-portions tend to prevent them from being withdrawn from the described position, but to increase the security of the connection 90 the end-portions are provided with ribs or corrugations, which enter corresponding corrugations 20 in the plate 12, adjacent to the openings through which the connecting- 95 member 17 passes, as shown in Fig. 3. The extremities of the air-tubes may be fixed to the air-chamber 15 in the usual manner, and the tubes are provided with outwardly projecting beads or ribs 21, 22 at the edges of the connecting-members 17, so as to prevent 100 the tubes from sliding within the members 17, and also to produce a neat finish and conceal the raw edges of the connecting-members.

The plate 12 serves not only as a part of 105 the means for connecting the air-tubes with the oil-font, but also as a part of the means for supporting the globe-lifter. This lifter is shown as comprising a cam-like arm 23 of a well known form, which cooperates 110

with a cranked wire 24 by which the globe-plate 25 is raised. The arm 23 is formed from wire continuously with a short shaft 26, and this shaft has its bearing in a sleeve 27. The sleeve is formed by bending a strip of sheet-metal, and the ends of this strip are passed downwardly through one of the openings in the plate 12 alongside the air-tube, and are arranged to lie between the plate and the adjacent end 19 of the connecting-member 17, as shown in Fig. 3.

The structure above described not only provides a strong and rigid form of connection between the oil-font and the air-tubes and other parts of the lantern, but it also facilitates the construction and assembling of the lantern, and avoids the injury to the finished appearance of the lantern which results from the usual operation of soldering the air-tubes and other parts to the oil-font. The tin-plate or other sheet-metal of which the lantern is constructed has a bright and clean appearance which is not destroyed by the mechanical operations of assembling the various parts, but where the assembling is completed by a soldering operation the metal is unavoidably soiled and tarnished, and thus the appearance of the lantern is impaired unless a special and expensive cleaning or finishing operation is afterward performed upon it. The present construction avoids this disadvantage by the substitution of mechanical operations for soldering, and it also produces a structure of more permanent strength, since soldered joints are liable, as is well known, to yield and break when subjected to repeated strains. Another advantage of the use of the connecting-plate 12 resides in the fact that letters or other devices may be stamped upon this plate, to take the place of those ordinarily stamped upon the top of the oil-font. In stamping such devices in the oil-font it has been found that if the impressions are deep

or sharp, the tin-plate of which tubular lanterns are ordinarily made is ruptured by the dies, so that leakage occurs from the oil-font. By stamping the devices in the plate 12, however, injury to the oil-font is avoided, and the impressions may be made as sharp and deep as is desired.

We claim:

1. In a tubular lantern, the combination, with an oil-font and air-tubes, of means, for connecting the oil-font with the air-tubes, comprising a plate lying on top of the oil-font and fixed thereto, and members interlocked with said plate and passing over the lower ends of the air-tubes.

2. In a tubular lantern, the combination of an oil-font provided with an annular lateral recess; parts associated with the oil-font; and means, for connecting said parts with the oil-font, comprising a plate lying on top of the oil-font and extending also, at its periphery, into said recess, and fastening-members passing over said parts and having their ends seated between the plate and the oil-font.

3. In a tubular lantern, the combination, with an oil-font and a part located above the oil-font, of a plate lying on top of the oil-font and below said part, the plate being fixed to the oil-font; and a fastening-member extending over said part and with its ends passing through the plate and lying between the plate and the oil-font.

4. In a tubular lantern, the combination, with an oil-font and a part located above the oil-font, of a plate lying on top of the oil-font and below said part, the plate being fixed to the oil-font; and a fastening-member extending over said part and with its ends passing through the plate and lying between the plate and the oil-font, said ends and the adjacent part of the plate being corrugated to resist withdrawal of said ends.

EDWARD J. McDADE.
THEODORE A. GLENDE.
